United States Patent Office

Des. 186,380
Patented Oct. 20, 1959

186,380

PICTURE FRAME OR SIMILAR ARTICLE

Henry F. Miller, Chicago, Ill.

Application April 17, 1959, Serial No. 55,549

Term of patent 14 years

(Cl. D29—20)

FIG. 3

FIG. 4

FIG. 5

Figure 1 is a front elevational view of a picture frame embodying my new design;

Figure 2 is a plan view of the picture frame;

Figure 3 is a cross-sectional view taken substantially along the lines III—III of Figure 1;

Figure 4 is an end elevational view of the picture frame; and

Figure 5 is a cross-sectional view taken substantially along the lines V—V of Figure 1.

I claim:

The ornamental design for a picture frame, substantially as shown.
